UNITED STATES PATENT OFFICE.

STEPHEN J. VAN KUREN, OF CEDAR RAPIDS, IOWA, ASSIGNOR TO J. G. CHERRY COMPANY, OF CEDAR RAPIDS, IOWA, A CORPORATION OF IOWA.

CHURN-TIMER.

1,371,455.

Specification of Letters Patent. Patented Mar. 15, 1921.

Application filed June 12, 1919. Serial No. 303,639.

To all whom it may concern:

Be it known that I, STEPHEN J. VAN KUREN, a citizen of the United States, residing at Cedar Rapids, in the county of 5 Linn and State of Iowa, have invented certain new and useful Improvements in Churn-Timers, of which the following is a specification.

This invention relates to timing devices 10 and it is especially designed and adapted for use in connection with churns to give a signal which will indicate to the operator when the butter working process is completed.

15 It is customary for the operator to time the butter working process by the revolutions of the churn drum, which operates at a comparatively low rate of speed, about six revolutions per minute, when working butter.

20 The object of this invention is to provide a timing device which can be set to give a signal after a predetermined number of revolutions of the drum so that the operator may be occupied in other duties during the 25 butter working process, knowing that he will receive ample warning from the timing device as the working process approaches completion.

A further and very important object of 30 the invention is to provide a device of this character without delicate or complicated parts but having a strong and substantial construction suitable for the conditions under which a butter process must necessarily 35 be conducted.

In the accompanying drawings I have 40 illustrated a preferred embodiment of the invention in which a bell is employed to be sounded as a signal, and referring thereto—

45 Figure 1 is a front elevation showing the device in its proper relation to an operating cam on a right hand churn, that is one in which the operating devices are located at the right end of the drum.

50 Fig. 2 is a sectional elevation of the device with the dial and bell removed.

Fig. 3 is a side elevation.

Fig. 4 is a top plan view.

Fig. 5 is a rear elevation.

55 Fig. 6 is a front elevation of the device adapted for a left hand churn, that is one in which the operating devices are located at the left end of the drum.

Figs. 7 and 8 are detail views of the 60 device for the left hand installation.

My invention broadly contemplates a device adapted for a right hand or for a left hand machine which can be mounted on the leg or standard supporting the drum, with the operating cam on the end of the drum, 60 or which can be mounted on the end of the drum, with the operating cam on the leg or standard. In the drawings I have illustrated the former construction in which the timer is mounted on a leg or standard 65 and the operating cam on the drum, but it will be readily understood that the position of these parts may be reversed within the intended scope of the appended claims.

The device constructed for a right hand 70 churn comprises a pivot which may be in the form of a rock shaft 9 (Figs 1-5) which is mounted in a support 10 securely fastened to the leg or standard 11 of the churn. A rocker 12 is rigidly mounted on the shaft 9 75 and carries a cam segment 13 at its upper end and a spur 14 below the cam. A notch 15 in this rocker engages a projection 16 on the support to limit the movement of the rocker (Fig. 5). A floating pawl 17 is pro- 80 vided with an opening 18 to loosely receive the spur 14 on which it is mounted, and the upper end of this pawl, which is a feed pawl, is arranged to engage the teeth of a peripheral flange 19 on a dial plate 20 which 85 is revolubly secured by a bolt 21 on the support. The pawl is held in engagement with the toothed flange by a spring 22 attached to the lower end of the pawl and to the support. A feather spring 23 is fastened 90 to the support to engage the toothed flange and serve as a holding pawl to prevent reverse movement of the dial plate.

The dial plate is provided with a cam 24 which is adapted to actuate the operating 95 member of a signal device, such as the plunger 25 of a bell 26. This bell may be of any suitable type but I prefer to provide a continuous ringing bell and to make the cam of such length that it will engage the 100 bell-operating member and continue to sound an alarm during a plurality of revolutions of the churn so that ample warning of the completion of the butter working process will be given, but a short cam may 105 answer the purpose if a correspondingly short signal is sufficient.

A cam 27 is mounted on the head of the churn, conveniently to a rib on the operating gear fast on the head (not shown). 110

This cam is adjusted so that the segment 13 will be positioned in its path of movement as the churn drum revolves. The segment may be thrown out of operative relation to the cam by means of a lever 28 pivoted on the support at 29. This lever is shown in normal position in full lines in Fig. 2, out of engagement with the rocker. When the lever is swung on its pivot its upper short end 28' 10 will ride over the rocker and depress the same to carry the segment out of the path of the cam and render the timing device inoperative.

For a left hand churn timer (Fig. 6) the segment 30 (Fig. 8) and the rocker 31 (Fig. 7) are made separately, the segment being mounted on the right end of the rock shaft 9 and the rocker being mounted on the left end of this shaft as in the right hand churn timer. In other respects the construction is the same as heretofore described and the operation of both constructions is identical.

In practice the device is mounted in any suitable position where the tripper segment 13 is adapted to be engaged and operated by a cam or other suitable device on the revolving drum of the churn. The operator will set the toothed dial by turning it clockwise until the tooth representing the predetermined number of revolutions desired is disposed opposite the plunger 25. The dial is provided with finger pieces 30 to facilitate this adjustment. Then the churn is placed in operation and each time the segment is tripped the feed pawl will advance the dial the distance of a tooth and the holding pawl will hold it in this position. The spring 22 serves to retain the feed pawl in place on the spur 14 as well as to hold it in operative engagement with the dial plate, and furthermore it holds the rocker arm and its segment normally in the path of the cam 27.

As the butter working process nears completion the cam 27 will be carried into operative engagement with the bell operating member 25 and sound an alarm, this alarm being continued as long as the cam continues in operative engagement with said member and preferably during several revolutions of the churn so that the operator will have ample opportunity to leave any other work upon which he may be engaged to resume his attention to the churn.

While the invention is particularly intended for use in connection with churning for timing the butter working process it can obviously be employed for many other purposes which will be readily suggested to those skilled in the art.

My improved device is strong and substantial in construction, it has no delicate or complicated mechanism which would soon become corroded and disordered under the moist conditions which prevail in cream-

eries, it can be easily applied to a churn, and it can be readily adjusted for operation.

I am aware that changes in the form and proportion of parts and in the details of construction of the invention may be made without departing from the spirit or sacrificing the advantages thereof, and I therefore reserve the right to make all such changes as fairly fall within the scope of the appended claims. For example, it is apparent that the cam 24 may be employed to close an electric circuit which will ring a bell or a buzzer, or flash a light, or produce any other kind of signal suitable for the purpose, it being necessary only to provide a member which will be actuated by the cam for this purpose.

I claim:

1. A timing device of the character described comprising a support, a toothed dial plate revolvably mounted on the support, teeth formed on the face of said dial plate about the periphery thereof, a feed pawl arranged to engage the teeth on said dial plate to advance the same a tooth at a time, a holding pawl to prevent reverse movement of the dial plate, means for operating said feed pawl, a prolonged operating signal device, and a cam on the periphery of said dial plate for operating said signal device.

2. A timing device of the character described comprising a support, a revolvble rocker shaft, a toothed dial plate revolvably mounted on the support, a spring controlled feed pawl yieldingly mounted on the said shaft and adapted to advance said dial plate a tooth at a time, a holding pawl to prevent reverse movement of the dial plate, a prolonged operating signal device, an operating member for said device, and means on the dial plate to actuate said operating member.

3. A timing device of the character described comprising a support, a revolvble rocker shaft, a toothed dial plate revolvably mounted on the support, a feed pawl mounted on the said shaft and arranged to engage and advance the dial plate a tooth at a time, a spring for holding the said shaft and the feed pawl in operative position, a prolonged operating signal device, an operating member for said signal device, and means on the dial plate for operating said member.

4. A timing device of the character described comprising a support, a revolvble rocker shaft, a toothed dial plate revolvably mounted on the support, a feed pawl carried by said shaft to advance the dial plate a tooth at a time, a prolonged operating signal device, a cam on the periphery of said dial plate for operating said signal device, and a lever on the support adapted to be engaged with said shaft to render the same inoperative.

5. A timing device of the character de-

scribed comprising a support, a revoluble rocker shaft, a segment on said shaft adapted to be engaged to operate said shaft, a dial plate, a pawl operated by said shaft to turn 5 the dial plate intermittently a step at a time, a prolonged operating signal device, and means on the dial plate for operating said signal device.

6. The combination of a support, a revoluble rocker shaft, a segment for operating said shaft, a dial plate, a pawl operated by

said shaft for turning the dial plate intermittently a step at a time, a prolonged operating signal device, means on the dial plate for operating said signal device, a revoluble 15 churn drum, and a cam on said drum for engaging said segment to operate said shaft.
